HOISTING APPARATUS

Walter Joseph Herbst, Chicago, Ill.

Application April 3, 1956, Serial No. 575,843

1 Claim. (Cl. 294—81)

This invention relates to an improved hoisting apparatus and, more particularly, pertains to a hoisting apparatus which is particularly adapted for use with die sets.

The prior art discloses a wide variety of hoisting means which are employed with die sets or similar plate members of substantially uniform construction and large bulk. However, these prior art devices are themselves of large bulk and cumbersome in operation. In addition, when utilized with a die set member, movement of the die set other than in a single vertical plane is usually impossible when the hoisted member is in an elevated position. Consequently, when the die set member is elevated, it remains in a single plane and is unable to be turned or otherwise moved for purposes of affixing a die member thereto or removing a die member therefrom, or otherwise engaging the dies affixed to the die set surface.

It is an object, therefore, of this invention to provide a hoisting apparatus, adapted for use with die set members or equivalent plate members, which enables the die set to be pivotally moved in the elevated position in a full circle of 360° whereby both surfaces thereof are readily accessible.

It is a further object of this invention to provide a hoisting apparatus which is composed of a few components, all of which are simple and inexpensive in design.

It is another object of this invention to provide a hoisting apparatus which assures safety in the course of operation.

It is still another object of this invention to provide a hoisting apparatus which is adapted to be used efficiently with any of a large number of die set members or similar members which vary greatly in size.

It is yet another object of this invention to provide a hoisting apparatus in which the supporting cables, comprising a part thereof, adjust their respective lengths to accommodate the size of the specific die set member engaged.

The above and other objects will become more apparent upon proceeding with the following description, accompanying drawing and appended claim.

In one embodiment of this invention, a crossbar member, which is composed of a durable material such as steel and which is resistant to flexing or other distortion, is supported by means of cables or other equivalent means. The crossbar is movable so as to be positioned above a die set member which is to be elevated and is disposed transversely to the longitudinal axis thereof. Disposed on the periphery of the crossbar member are two adjustable ring members which are securable to the periphery of the crossbar member by means of set screws which threadedly engage each of the ring members. Affixed to opposed end limits of the crossbar by suitable means are two flexible cable members of sufficient strength to support any die set member to be engaged in the normal course of operation.

2

The flexible cable members depend from the crossbar member after first passing through the adjustable ring member disposed closer thereto. It is thus apparent that the flexible cable members have a portion thereof disposed parallel to the length of the crossbar member, which portion defines the distance each of the adjustable ring members is disposed from the nearer end of the crossbar member. Each of the flexible cable members, after passing through its respective adjustable ring members, depends downwardly, normally to the crossbar member, and has a plate member of steel, or other material of equivalent strength, attached thereto. Each of the plates has a keyhole slot disposed in the central portion thereof. It is the purpose of these slotted plate members to engage in interlocking relationship, projecting stud members having a central reduced neck portion. These studs are affixed to opposed die set edge portions and disposed on an axis passing through the center of gravity of an underlying die set member which is to be elevated.

In the normal course of the lifting operation, the crossbar member is lowered until it is disposed adjacent the upper surface of the die set member to be lifted. The adjustable ring members are then fixedly positioned on the crossbar member by means of their respective set screws so as to have an interval therebetween substantially equal to the width of the die set member to be elevated. The interval between each end limit of the crossbar and its adjacent adjustable ring should also be equal. Consequently, the lengths of the depending flexible cables must, of necessity, be equal. The plate members, having the keyhole slots disposed therein with the narrow portion of the slot disposed at the lowermost portion of the slot, then engage the opposed stud members affixed to the die set member. This engagement is effected by means of the reduced neck portion of each stud member interlocking with the keyhole slot disposed in each of the depending plate members. Since the opposed stud members are disposed in an aligned relation with respect to the center of gravity of the die set member, the latter, upon being elevated, may be turned with ease and access readily had to the under-surface or any other surface portion thereof.

For a more complete understanding of this invention, reference should now be had to the drawings, wherein:

Figure 1 is a perspective view illustrating the hoisting apparatus of this invention engaged to a die set member, and

Fig. 2 is a fragmentary perspective view of the die set disposed over a die set member prior to engagement therewith.

Referring now to the drawings and more particularly to Fig. 1, a hoisting apparatus 10 is illustrated disposed above two cooperating die set members 12 and 14 which are adapted to have die members, not shown, affixed to their opposed surfaces 16 and 18, respectively. Such opposed die members are adapted to mutually cooperate during the reciprocal movement of one or both die set members on guide posts 46, as illustrated in Fig. 2.

The hoisting apparatus 10 comprises a crossbar member 20 which may be supported by the two cable members 22 of equal length. The two cable members may be secured to the opposed end limits of the crossbar by welding or other suitable means and are secured at their remaining end limits to a supporting ring member 24 which may, in turn, be supported by a main cable member 26. Disposed on the periphery of the crossbar 20 are two adjustable ring members 28, each of which is tapped, enabling set screws 30 to threadedly engage the tapped apertures and fixedly secure each of the adjustable ring members 28 to the periphery of the crossbar 20.

Two cable members 32 depend from the crossbar 20 and comprise two support means which are adapted to engage either of the underlying die set members 12 or 14 and elevate the same. It will be noted that the supporting cables 32 are affixed at their upper end limits, as illustrated, by means of welding, or other means of securement, at 34 to the opposed end limits of the crossbar 20. It will also be noted that each of the flexible cable members 32, before depending to engage the die set members, pass through the adjustable ring member 28 which is disposed adjacent thereto.

Affixed to the lower end limit of each cable member 32 is, in this instance, a plate member 36. The point of connection between a cable 32 and a plate 36 is such as to enable the plates to hang with their opposed surfaces disposed substantially parallel to the adjacent sides of the die set members. Disposed in each of these plate members is a keyhole slot 38 which, as seen more clearly in Fig. 2, has a narrow bottom portion 38a and an enlarged upper portion 38b communicating therewith.

Fixedly secured, in this instance, to opposed longitudinal edges or sides of each die set member 12 or 14 are laterally projecting stud members 40, each of which has a reduced central neck portion 42, more clearly seen in Fig. 2. The stud members 40 are disposed along a transverse axis passing through the center of gravity of a die set member 12 or 14, for purposes which will hereinafter be made apparent.

In the normal course of operation, the interval between adjustable rings 28 must first be set on the crossbar and should be substantially equal to the width of the die set to be raised in the manner illustrated in Fig. 2, whereby the cable portions 32, depending from said rings 28, are substantially parallel. It is also apparent that, for purposes of balance, the intervals between each adjustable ring 28 and the end limit of the crossbar disposed closer thereto should be substantially equal. Notches or other markings 21 may be disposed along the length of the bar 20 to facilitate proper positioning of the rings 28.

In attaching the plates 36 to the stud members 40, the crossbar member 20 is initially lowered a sufficient distance to enable the stud members 40 to pass through the corresponding slot portions 38b so as to permit the reduced neck portion 42 of each projecting stud member 40 to be seated in slot portions 38a. After such engagement, the stud members are securely locked in the plates, and relative lateral movement between the die set member, engaged, and the plate members is obviated. After the plate members 36 have engaged the stud members 40 and interlocked therewith, the hoisting apparatus 10 is elevated by an appropriate motive means, not shown, along with the die set member engaged. It will be apparent from Fig. 1 that, since the stud members 40 are disposed along an axis passing through the center of gravity of an engaged die set member, the latter may be pivoted about such axis with ease when the die set is in an elevated position so that access may be readily had to the undersurface of either die set member. It will also be apparent from Fig. 1 that, since the hoisting apparatus and the engaged die set member are suspended by a single cable member 26, the entire apparatus may be rotated in a horizontal plane to facilitate access to various surface portions of the die set. The upper end limit of the cable 26 may be connected to a common universal type joint, well known in the art, which allows the cable to rotate without twisting thereof. Also, the cable may obviously be affixed to an overhead motive means, not shown, which in addition to reciprocally moving cable 26 and parts attached thereto, may transport the same along a monorail or the like.

The length of the cable members 32 should be such as to enable the die set member, engaged, to rotate a full 180° without engaging the crossbar 20. It will be noted that the wider the die set member engaged the

longer must be the depending length of each cable 32. As the width of the die set member decreases, the interval between the adjustable rings 28 will correspondingly decrease, and the length of the depending cables 32 will be decreased. Consequently, because of the arrangement whereby the supporting cables 32 pass through the adjustable rings 28, the hoisting device 10 will compensate for the size of the die set engaged.

The release of a die set member, engaged, is quite simple. After the appropriate work has been done on the elevated die set member, it is lowered to engage appropriate guide posts 46 or other cooperating equivalent parts and lowered a sufficient amount to enable the plate members 36 to become disengaged from the projecting studs 40. This latter disengagement is relatively simple and is effected merely by pushing the plate member 36 in a downward direction enabling the projecting stud to pass through the enlarged portions of the keyhole slots 38.

While the studs 40 are illustrated as being disposed on the opposite elongated edges of one of the die sets, they may, if desired, be disposed at the center of gravity of the opposed end faces of the die set. Likewise, while plates 36 are shown provided with keyhole-type slots 38, it is within the scope of this invention for the plates to be provided with transversely extending pins which might removably engage selective bores formed along the edges of the die set. Furthermore, if the hoisted die set should be unbalanced by reason of the arrangement of the die members, not shown, on the face thereof, a guide cable, not shown, may be affixed to the light side of the die set so that the operator might readily counterbalance the weighty side of the die set by pulling downwardly on the cable so as to maintain the die set in a substantially horizontal plane.

While the apparatus has heretofore been described in relation to a hoisting operation, it is to be understood, of course, that it has application in handling a heavy workpiece in, for example, a horizontal plane where sliding such workpiece from one place to a second place in the same plane is desired. Likewise, the apparatus is readily adapted for the location of one die set with respect to another, when the latter is not disposed in horizontal plane.

It is thus apparent that a hoisting apparatus particularly adapted for use with die set members has been provided which is efficient in operation, simple in details of construction and which, in the normal course of use, because of the novel method of engaging the die set member, may be freely moved in the elevated position whereby access to the desired surfaces thereof is readily had.

It is obvious that many substitutions and modifications of the illustrated device may be effected which will still remain within the inventive concepts herein disclosed. It is intended, therefore, that this invention be limited only by the scope of the appended claim.

I claim:

In a hoisting apparatus for die sets or the like, a horizontally disposed, elongated, rigid supporting member, two flexible cable members affixed to opposed end limits of said supporting member, a pair of cable-engaging means operatively connected to said cable members and mounted on said supporting member for independent, longitudinal movement with respect thereto to predetermined positions of adjustment on said supporting member, the lengths of the portions of said cable members depending from said supporting member being dependent upon the predetermined positions of adjustment of said cable-engaging means on said supporting member, and locking means cooperating with each of said cable-engaging means and said supporting member to retain said cable-engaging means in selected positions of adjustment.
